UNITED STATES PATENT OFFICE.

EDWARD TRIST, OF PITTSBURGH, PENNSYLVANIA.

GAS STOVE AND RANGE.

1,144,158.

Specification of Letters Patent. Patented June 22, 1915.

Application filed March 14, 1914. Serial No. 824,721.

To all whom it may concern:

Be it known that I, EDWARD TRIST, a subject of the King of England, residing at Pittsburgh, in the county of Allegheny and State of Pennsylvania, have invented certain new and useful Improvements in Gas Stoves and Ranges, of which the following is a specification, reference being had therein to the accompanying drawing.

10 This invention relates to gas stoves and ranges, and has for its object to provide a gas stove or range, with means, in a manner as hereinafter set forth, for retarding the flow of the heating units, under such circumstances increasing the efficiency of the stove.

15 Further objects of the invention are to provide a gas stove or range which is simple in its construction and arrangement, strong, durable, efficient and convenient in its use, readily set up and comparatively inexpensive to manufacture.

20 With the foregoing and other objects in view the invention consists of the novel construction, combination and arrangement of parts as hereinafter more specifically described and illustrated in the accompanying drawings, wherein is shown an embodiment of the invention, but it is to be understood that changes, variations and modifications 25 can be resorted to which come within the scope of the claim hereunto appended.

25 In the drawings wherein like reference characters denote corresponding parts throughout the several views:—Figure 1 is an elevation, broken away, of a gas range in accordance with this invention. Fig. 2 is a side view, partly in section, with parts broken away to show the structure of a gas range in accordance with this invention.

30 Referring to the drawings in detail, 3 denotes the body portion of a gas range, and which has its bottom 4 provided with air inlet openings 5. Within the body portion 3 is arranged a rectangular shell 6 forming 35 an oven 7, which is closed at its rear by the back wall 8 of the body portion 3, and is closed at its front by a door 9, which is hinged as at 10, to the front wall 11 of the body portion 3. Arranged forwardly of the 40 front of the body portion 3, near the top thereof, is a gas supply pipe 12, which is provided with valves 13 for controlling the supply of gas to burners at the top of the range, and said pipe 12 has a downward extension 14, which communicates with a feed pipe 15; the latter has an extension 16, which

45 opens into a gas and air mixer 17, carried on the outer end of a burner tube 18, the latter having outlets 19, and the said tube is positioned between the bottom of the oven 7 and bottom 4 of the body portion 3. The foregoing elements are of known construction.

The shell 6 is of such size with respect to the body portion 3 to form heating spaces 19^a—20 at the sides of the shell, a heating 50 space 21 at the bottom of the shell, and a heating space 22 at the top of the shell.

Secured to the outer face of each side of the shell 6 is a series of spaced heat retarders, and each of which consists of a plate 23 55 provided with longitudinal flanges 25. One of the flanges is arranged above the other, and each of the flanges depend downwardly at an inclination. The flanges are of the same length as the length of their respective 60 plate, and each plate is of a length equal to the length of the shell, and is fixedly secured to the shell by the hold-fast devices 26.

The inner face of each of the side walls of the body portion 3 is provided with a 65 series of superposed spaced seats 27, and arranged in each of said seats is the depending flange 28 of an upwardly inclined strip 29, which constitutes a heat retarder, and the said strips 29 are alternately disposed with respect to the flanges 25, and are so arranged that they are positioned centrally with respect to the flanges 25. The flanges 25 extend at a greater inclination than the strips 29, and the said strips 29 are 70 fixedly secured in position by the hold-fast devices 30.

The flanges 25 upon one side of the shell 6 extend in an opposite direction with respect to the flanges 25 upon the other side of the 75 shell 6, and the strips 29 upon one side of the body portion 3 extend in an opposite direction with respect to the strips upon the other side.

The flanges 25 and strips 29 retard the 80 passage of the heat units as they travel through the spaces 19^a—20, under such conditions increasing the efficiency of the oven as the same is heated in a uniform manner, due to the retarders, and further heated 85 more quickly as the heat units do not pass rapidly through the spaces 19^a—20.

What I claim is:—

90 A stove of the class described comprising a body, a shell arranged therein in spaced 95 relation to the side walls thereof, a plurality of seats arranged in superposed relation to

one another on the inner faces of the side walls of said body, heat retarders formed of angular metal arranged in the seats and having portions thereof projected upwardly within the body, and additional heat retarders of channel shaped design secured to the side walls of the shell and having portions thereof projecting downwardly and out

wardly toward the aforesaid retarders to alternate the latter.

In testimony whereof I affix my signature in the presence of two witnesses.

10

EDWARD TRIST.
